UNITED STATES PATENT OFFICE.

WILLIAM GOWLLAND AND CHARLES S. GOWLLAND, OF CROYDON, ENGLAND.

OPHTHALMOMETER.

1,110,197.

Specification of Letters Patent.

Patented Sept. 8, 1914.

Application filed October 31, 1910. Serial No. 590,088.

To all whom it may concern:

Be it known that we, WILLIAM GOWLLAND and CHARLES SEPTIMUS GOWLLAND, subjects of George V, King of Great Britain and Ireland, and residing at Morland Road, Croydon, in the county of Surrey, England, have invented certain new and useful Improvements in Ophthalmometers, of which the following is a specification.

In ophthalmometers for the determination of corneal astigmatism, as heretofore constructed, the amount of movement imparted to the prisms which multiply the images corresponds to the amount of movement imparted to the registering means through the medium of which the prisms are moved, and in instruments in which the prisms are moved transversely of the optical axis and are of varying strength, the registering means do not register the correct displacement of the images. It is chiefly this defect which the present invention has been designed to overcome. In carrying out this invention, we move the prisms through the medium of a suitably shaped cam surface, preferably a snail-cam. The term "cam-surface" is to be understood as including a straight but sloping surface which is adapted to move the prisms in the required manner. In instruments as heretofore constructed in which the prisms are moved longitudinally of the optical axis, although the displacement of the images generally corresponds to the amount of movement imparted to the prisms, we nevertheless apply the present invention thereto in order to simplify the construction of the instrument and cheapen its production so that any inaccuracy that there may be in the prisms can be compensated for by suitably shaping the cam-surface. Again, by suitably shaping the cam-surface we are enabled to employ de-centered lenses or other means for multiplying the images. Another object of this invention is to arrange the recording devices concentrically with the optical axis of the instrument so that the construction of the latter is improved and rendered more compact than formerly.

A further object is to adapt the instrument so as to make it a "single position" one.

According to this invention, in that class of ophthalmometer in which the prisms for multiplying the images are moved trans-

versely of the optical axis, we fix the plate which carries the markings indicating the radii of curvature and also the curvature in dioptres, (known as the "middle dial") to and concentric with the telescope tube, and on either side of the slides in which the said prisms are mounted we arrange the other registering means comprising movable disks (hereinafter termed "registering-wheels") similarly concentric, their opposing or inner faces having flanges one of which overlaps the other. One of the registering wheels is graduated and the other carries a pointer which extends over the edge of the graduated registering wheel so as to be capable of use in conjunction with the markings on the middle-dial. On the inner face of each registering wheel we fix a snail-cam. The slides which carry the prisms are provided with means for operatively connecting them with the snail-cams, such means consisting preferably of a roller projecting from each of the said slides. The rollers are kept up to the edge of the cams, so that, when the registering wheels are operated, movement is imparted to the prisms. In ophthalmometers of the class in which the prisms for multiplying the images are moved longitudinally of the optical axis, one of the wheels, constituting the registering means, is provided with a boss having a snail-cam surface formed in one end thereof. The slide which carries the said prisms is in operative connection with the boss, and the cam surface is kept in engagement with a stationary roller provided on the telescope tube, so that when the boss rotates the necessary movement is imparted to the prisms. In order to provide a "single position" instrument, we rotate the prisms, and sometimes the objectives as well, instead of finding the secondary axis by rotation of the mires as formerly.

In order that this invention may be clearly understood and readily carried into effect, we will proceed to describe the same with reference to the accompanying drawings, of which Figures 1 to 4 show parts of an ophthalmometer in which the prisms are moved transversely of the optical axis.

Fig. 1 shows in elevation an inner view of one of the registering-wheels and the mechanism for moving the prisms, the snail-cam shown being one which belongs to the other registering-wheel, the latter having

been removed in order to expose the said mechanism to view. Fig. 2 is a front elevation of the mechanism for moving the said prisms, a portion thereof being removed, 5 however, in order to clearly show one of the slides by which one of the usual sets of prisms is moved. Fig. 3 shows the relative position of the two registering-wheels, the mechanism for carrying the said prisms and 10 the middle-dial, the registering-wheels and middle-dial being shown in central section, and the said mechanism in side elevation. Fig. 4 is a part elevation (on a smaller scale) of the left-hand side of Fig. 3. Figs. 5 to 15 show parts of an ophthalmometer in which the said prisms are moved longitudinally of the optical axis, Fig. 5 showing, in side elevation the snail cam carried by one of the registering-wheels and encircling the telescope-tube, the cam being shown engaging a roller which connects with the slide for moving the said prisms. Fig. 6 is an end elevation of the right-hand end of Fig. 5, Fig. 7 is a section on line 7—7 of Fig. 6. 20 Fig. 8 is a front elevation of a flexible cam, and Figs. 9 and 10 are side elevation and sectional plan respectively, of so much of a keratometer or ophthalmometer as it is necessary to show in order to aid the description of that part of this invention which relates to the provision of a "single position" instrument. Figs. 11 and 12 are sections across d' and t' respectively of Fig. 10. Figs. 13 and 14 each show a portion of 30 the flexible cam of Fig. 8 with a detail of construction in operative connection therewith; and Fig. 15 shows a modified construction of a portion of Fig. 10.

Like letters refer to like parts throughout 40 the drawings.

Referring to Figs. 1 to 4 of the drawings, a represents a portion of the usual telescope-tube of the instrument secured to bosses b , b' , which are attached to the guides c , c , 45 wherein the slides d , d , work for the purpose of operating the prisms, these being held in place by clips e , e , this arrangement of apparatus, however, being as usual, and forming no part of our present invention. 50 f , f' , are the registering-wheels arranged concentrically with the telescope-tube a , the wheel f being of disk form and the wheel f' , in the form of a spider. The outer portion of the wheel f is of openwork construction 55 and has a ring of celluloid f^2 fixed thereto, as shown in Fig. 4. The ring of celluloid f^2 contains the necessary markings, shown at f^3 , as will be well understood, and is illuminated by light transmitted through the 60 spider-wheel f' , from the usual lamps (not shown) which illuminate the mires. On the inner face of the registering-wheels f , f' , we fix the snail-cams g , g , which may, if desired, be fixed in position by means of 65 screws or the like passed through slots

formed in them, said slots being for the purpose of adjusting the position of the cams on the registering-wheels f , f' . The cams g , g , are alike in shape, one of them being shown in face view at g in Fig. 1, and they 70 are arranged so that the telescope tube a passes through them. The slides d , d , are operatively connected with the snail-cams g , g , in any suitable manner, but preferably by means of rollers h , h , mounted on studs 75 h' , h' , which project from the slides d , d , the rollers being kept up to the edge of the cams by means of helical springs j , j , which are fixed at one end to the guides c , c , and at the other end to the slides d , d . The 80 method of attachment of these springs is shown most clearly in Figs. 1 and 2, j , j' , showing where they are attached to the guide, and j^2 , j^2 , showing where they are attached to the slide. In Fig. 3 the springs 85 j , j , are of the same construction and they are arranged in the same way as the springs j , j , in Figs. 1 and 2.

The wheels f , f' , with their cams g , g , are held friction tight on the bosses b , b' , by 90 means of ordinary spring-collars k , k fitting into circumferential grooves b^2 , b^2 formed in the bosses b , b' . To the spider-wheel f' is fixed a pointer l which extends over the edge of the wheel f . The portion of this 95 pointer which overlaps the ring of celluloid f^2 is open, as shown at l' , in order that the markings f^3 may be read, an index l^2 being provided on the pointer l to facilitate this reading. m is the middle-dial which is 100 fixed to the boss b by means of a collar m' and the radii of curvature marked thereon are read off by means of the inner index l^3 of the pointer l . m^2 is a pointer attached to the telescope-tube a and projecting 105 through a partially circumferential slot m^3 formed in the collar m' in order that the amount of rotation of the telescope tube may be read on the middle-dial m . The means for fixing the pointer m^2 in position consist 110 of a tongue or base portion m^4 , forming part of the pointer, tightly fitting into a shallow recess formed in the inner face of the telescope tube a , and a keeper m^5 , which fits friction tight inside the telescope tube and 115 retains the tongue or base portion m^4 in place. The flanges on the inner face of the registering-wheels f , f' , are shown at f^4 , f^4 , and it will be seen that they inclose the mechanism which carries the prisms and 120 protect the same from dust.

The construction of the cams g , g , and their action on the prism-slides d , d , being alike, it will only be necessary to describe the construction and action of one of them, 125 and this will be done with reference to the one shown in Fig. 1, which is assumed to be fixed to its registering-wheel f . Depending upon the direction of rotation of the registering-wheel f , the cam g , always bearing as 130

it does on the roller h mounted on the prism slide, will cause the prisms carried by the slide d to be moved in one direction or the other across the optical axis of the instrument. The pitch of the cam is such that for a given angular movement of the registering-wheel to which it is fixed, (no matter what the position of the registering-wheel) the amount of displacement of the images is always a constant quantity, or sufficiently constant for most practical purposes. The cam we find most suitable is the snail-cam as shown at g . If it is found that the edge of the cam, although truly formed, does not produce sufficiently accurate results, due possibly to abnormal irregularities in the prisms, it is rubbed away where necessary in order to produce the required amount of travel of the prisms.

Referring now to Figs. 5 to 7, on the telescope-tube a are rotatably mounted the two registering-wheels f, f' . g is the cam surface formed in the outer end of the boss f^5 fixed to the registering-wheel f . A helical spring j presses at one end on a collar o fixed to the telescope-tube and at the other end on the registering-wheel f in order to keep the cam-surface always in engagement with a roller h which is mounted on a stud h' fixed in the telescope-tube a . In the latter two slots a', a' , are formed through which screws q, q , are passed, screwing into a ring d in which the prisms for multiplying the images are intended to be mounted. The heads of the screws q, q , project beyond the telescope-tube a and are located in a channel f^7 formed in the inner face of the boss f^5 . As in Figs. 1 to 4, f' is a spider-wheel, which is rotatably mounted on the telescope-tube a , being kept in place thereon between the collar o and another collar r fixed to the telescope-tube. To this spider-wheel is fixed to a pointer l extending across to and in front of the face of the registering wheel f , which is provided with the necessary markings as in Fig. 4, the construction of this pointer being the same as in Figs. 3 and 4, excepting that the inner index l^8 is dispensed with. Describing the operation of the apparatus shown in Figs. 5 to 7, when the registering-wheel f is rotated it is caused to move along the telescope-tube a in one direction or the other, depending upon the direction of rotation, as will be well understood. As the wheel moves along it carries the slide d along with it. The pitch of the cam g is determined in the same way as the pitch of the cams described above in connection with Fig. 1.

In some cases, according to this invention, the cam is one which is flexible, or the path of which is adjustable. An example of such a cam is shown in Fig. 8. In this figure, s is a frame or skeleton conveniently of channel section at the inner end of which is formed a hole s' adapted to fit over the telescope tube, slots s^2 being provided therein for the purpose of adjustably securing it to the registering-wheels. The flexible portion of this cam is a clock-spring s^3 having its inner edge resting on or lying near to the bed of the channel and its outer edge free. Screws s^4, s^4 , are screwed through the sides of the frame or skeleton and their inner ends bear on the opposite sides of the clock-spring s^3 . In order to connect this cam with the means which carry the prisms for multiplying the images, said means may be provided with a rotatable stud h (Fig. 13) which projects therefrom and is provided with a slit h^2 at its end through which the projecting free edge of the clock-spring s^3 passes, or the stud may be replaced by a pair of rollers h, h , (Fig. 14) arranged so that the free edge of the clock-spring works between them. When the instrument has been set up, the clock-spring s^3 can be adjusted by the screws s^4, s^4 so as to produce the desired amount of travel of the prisms for a given movement of the means by which they are operated.

In some cases, in accordance with this invention, we use a cam or the like for the purpose of giving a regular movement to the said prisms by imparting a regular movement to the registering-means.

The apparatus shown in Figs. 9, 10, 11, and 12 will now be described. Within the telescope tube a is slidably fitted an inner body t furnished at the end near the eyepiece n of the instrument with a handle t' which projects through a quadrant slot a^2 formed in the telescope-tube. Within the inner body t is slidably fitted the prism box d and the objective box v . The prism box d has a pin d' projecting into a slot t^2 formed in the inner body, and it also carries a sleeve t^3 which is loosely journaled in its exterior surface and carries a pin t^4 projecting through an opening t^5 conveniently of rectangular shape formed in the inner body t , and into a slot a^3 in the telescope-tube. The diaphragm, which has two apertures arranged one on each side of its center in a line at right-angles to the prisms, is arranged between the objectives in the box v , and has a pin w which projects through a quadrant slot v' in the box v , and into a slot t^6 in the inner body.

In operation, the handle t' is first placed at one end of the slot a^2 , and then the axis of astigmatism is found as usual, namely, by rotating the telescope tube a and the mires by means of the handle x . This axis having been found, the handle t' is moved through the entire length of slot a^2 thereby causing the prisms to be rotated through an angle of 90° whereby the secondary axis is obtained without further rotation of the mires as was formerly the case. It will

thus be seen that the instrument is a "single position" one. During the rotation of the inner body, the loose sleeve t^3 remains stationary, owing to its pin t^4 engaging the sides of the slot a^3 , and the diaphragm is carried around by reason of its pin w engaging the sides of the slot t^6 , said pin w moving along the slot v' in the box v , which latter is thus left stationary. Sometimes, however, in accordance with this invention, we make provision for the objectives to be carried around by and with the inner body, which may be done by dispensing with the slot v' . The secondary axis having been found, the wheel f is rotated in order to move the prisms longitudinally for the purpose of ascertaining the amount of astigmatism. During the rotation of the wheel f its cam surface g bears on the pin t^4 thereby moving it along the slot a^3 , and consequently the pin d' travels along the slot t^2 , the cam surface g and the pin t^4 being kept in engagement with one another by means of the spring j pressing on one end of the prism box.

We claim:

1. In ophthalmometers, the combination with the prism-carrying means, of abutments thereon, cams for operating the prism-carrying means, and means for keeping the abutments and cams in engagement with one another.
2. In ophthalmometers, the combination with the prism-carrying means, of flexible cams for operating same, and means for actuating the cams.
3. In ophthalmometers, the combination with the prism-carrying means, of cams for operating the same, the path of said cams being adjustable, and means for actuating the cams.
4. In ophthalmometers, the combination with the prism-carrying means, of registering-wheels arranged one on each side of same and concentrically with the horizontal tubular portion thereof, and flanges on the

inner faces of said registering-wheels and overlapping one another.

5. In ophthalmometers, the combination with the horizontal tubular portion thereof of a registering wheel arranged concentrically therewith, and a light-transmitting scale carried by an openwork part of said registering-wheel.

6. In ophthalmometers, the combination with the horizontal tubular portion thereof, of a pair of registering-wheels arranged concentrically with said tubular portion, a scale on one of said wheels, and a pointer fixed to the other of said wheels and extending to the scale-carrying wheel and overhanging the scale.

7. In ophthalmometers, the combination with the horizontal tubular portion thereof, of a "middle-dial" and a pair of registering-wheels all arranged concentrically with said tubular portion, a scale on the "middle-dial", a scale on one of said wheels, and a pointer fixed to the other of said wheels and extending to and overhanging the scale-carrying wheel and "middle-dial".

8. In ophthalmometers, the combination with the telescope tube and encircling collar, of a "middle-dial" arranged concentrically therewith and carried by said collar, said collar having a partially circumferential slot and a pointer attached to the telescope tube and extending through the slot so as to be capable of use in conjunction with the "middle-dial".

In witness whereof we have hereunto set our hands in the presence of two witnesses.
